CLAIM

The ornamental design for chaps, as shown and described.

DESCRIPTION

FIG. 1 is a front perspective view of chaps, showing my new design, shown in use;

FIG. 2 is a rear perspective view thereof, shown in use;

FIG. 3 is right side elevational view of the right leg portion thereof, shown in a zipped and flat condition;

FIG. 4 is a left side elevational view thereof;

FIG. 5 is a front elevational view thereof;

FIG. 6 is a rear elevational view thereof;

FIG. 7 is a front elevational view of the exterior thereof, shown in an unzipped, flat, and fully opened condition; and, FIG. 8 is a front elevational view of the interior thereof, shown in an unzipped, flat, and fully opened condition.

The broken lines depicting the human form are for illustrative purposes only and form no part of the claimed design.

The lighter weight dashed lines shown on the chaps represents a stitching line.
